UNITED STATES PATENT OFFICE

2,099,383

HEATING APPARATUS

William Anderson, Williamsport, Pa., assignor to
 Lycoming Manufacturing Company, Williams-
 port, Pa., a corporation of Pennsylvania

Application May 1, 1937, Serial No. 140,141

10 Claims. (Cl. 122—32)

The present invention relates generally to heating apparatus. More particularly the invention relates to that type of heating apparatus which is designed primarily for use in home or domestic heating and comprises as the main or essential parts thereof a boiler with a submerged hot water coil in the upper portion of the combined water and steam chamber thereof, a burner in front of the boiler for firing the latter, and a sheet metal jacket which surrounds the boiler and burner, serves normally to protect as well as conceal the externally disposed parts of the burner and also the fire and flue doors of the boiler and has hinged doors at the front thereof whereby access may be had to the burner and boiler when desired.

One object of the invention is to provide a heating apparatus of this type which is an improvement upon previously designed apparatus of the same general character by reason of the fact that the ends of the hot water coil in the upper portion of the combined water and steam chamber of the boiler instead of passing either through one of the side walls of the boiler and the contiguous side wall of the jacket or the front wall of the boiler and the jacket front and thus causing disposition of the water inlet and outlet pipes at either the side of the jacket or the jacket front where they not only would take up space but also might interfere with ready control or adjustment of the boiler and burner, pass through the back wall of the boiler and are there connected by detachable connections to the water inlet and outlet pipes.

Another object of the invention is to provide a heating apparatus of the last mentioned character in which the boiler embodies in the front wall thereof a plate closed opening which is disposed above the flue door and in substantial registry or horizontal alignment with the hot water coil and upon removal of the plate and also opening of the doors of the jacket and disconnection of the ends of the hot water coil from the inlet and outlet pipes permits the coil to be removed from the boiler for cleaning or replacement purposes.

A still further object of the invention is to provide a heating apparatus of the type under consideration which is generally of new and improved construction and due to the arrangement and manner of connecting the hot water coil may be installed readily.

Other objects of the invention and the various advantages and characteristics of the present heating apparatus will be apparent from a con-

sideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a fragmentary perspective of a 10 heating apparatus embodying the invention;

Figure 2 is a fragmentary perspective of the boiler of the apparatus showing in detail the design and arrangement of the hot water coil;

Figure 3 is an enlarged horizontal sectional 15 view of the apparatus; and

Figure 4 is a detail sectional view of one of the detachable connections between the ends of the hot water coil and the inlet and outlet pipes.

The heating apparatus which is shown in the drawing constitutes the preferred embodiment 20 of the invention. It is adapted primarily for home or domestic heating and comprises a boiler 5, a burner 6 for firing the boiler, and a sheet metal jacket 7 around the boiler and burner. 25

The boiler for the most part is of standard or conventional design and embodies an outer shell 8, an inner shell 9, and a hot water coil 10. The outer shell is fabricated from sheet steel and consists of a pair of side walls 11, a front 30 wall 12, a back wall 13, a top 14 and a bottom 15, and has a combustion chamber 16 in the bottom portion thereof. The top 14 of the outer shell is arched and embodies a steam outlet 17. It extends between and is formed integrally with 35 the upper ends of the sides 11 and together with the sides serves to hold the front wall and back wall in spaced relation. The inner shell is disposed in the central portion of the outer shell and forms within its lower portion the upper part 40 of the combustion chamber 16. It defines with the top 14 and the upper portions of the side walls and front and back walls of the outer shell a combined water and steam chamber 18 in the upper portion of the boiler and is spaced in 45 inwardly from the central portions of the side walls and front and back walls of the outer shell to form a water jacket 19 around the upper portion of the combustion chamber. As shown in Figure 2, this water jacket communicates with 50 the combined water and steam chamber 18 in the upper portion of the boiler. The front wall 12 of the outer shell embodies a pair of vertically disposed substantially rectangular openings 20 and 21 which communicate respectively with the 55

lower and upper portions of the combustion chamber. The opening 20 is disposed in the extreme lower portion of the front wall of the outer shell and is closed by means of a plate 22 which is removably secured in place by means of bolts 23. The upper opening 21 is normally closed by a fire door 24. The inner shell 8, as shown in Figure 2, embodies an upwardly extending enlargement 25 at the rear upper portion thereof. This enlargement communicates with and forms a part of the combustion chamber 16 and is connected by way of horizontally extending flues 26 to a box-like member 27 which fits against and is secured to the upper portion 15 of the front wall 12 of the outer shell. The enlargement 25 and the flues 26 are disposed in the combined water and steam chamber 18 and the products of combustion occurring during firing of the boiler flow successively therethrough 20 to the box-like structure 27. From this structure the products of combustion flow rearwards through horizontally extending flues 28 to an externally disposed smoke box 29 on the upper portion of the back wall 13 of the outer boiler shell. 25 The flues 28 are disposed above the flues 26 and extend between the upper portion of the box-like structure 27 and the back wall 13. The front wall 12 of the outer shell embodies an opening 30 above the fire door 24. This opening communicates with the box-like structure 27 and is normally closed by a flue door 31. Water is supplied to the combined water and steam chamber 18 by piping, not shown, and is maintained within the chamber at a level slightly beneath the top 35 14 of the outer shell, as well understood in the art.

The hot water coil 10 is adapted during operation of the boiler to heat water for domestic use. It is M-shaped, as shown in Figure 2 of the drawing, and is connected to a storage tank (not shown) by a water inlet pipe 32 and a water outlet pipe 33. The latter are located at the back of the boiler and are vertically offset so that during operation of the boiler and resultant heating of the coil 10, water flows from the tank through the pipe 32 and thence through the coil and back to the tank via the outlet pipe 33 as a result of the thermo-siphonic action which takes place. The coil 10 is disposed directly over the flues 28 and is located at such a level within the combined water and steam chamber 18 that it is fully and completely immersed in the water. The ends of the coil are disposed adjacent to the back wall 13 of the outer shell of the boiler and are connected to the pipes 32 and 33 by detachable connections 34. These connections comprise coupling sleeves 35 and nuts 36. The sleeves extend through holes 37 in the back wall 13 of the outer shell of the boiler and have internal screw threads 38 in the outer or rear ends thereof for connection to external screw threads on the water inlet and outlet pipes 32 and 33. The inner or front ends of the sleeves surround and are welded or otherwise fixedly secured to the ends of the hot water coil 10 and have outwardly extending annular flanges 39. The nuts 36 are mounted on external screw threads 40 on the outer ends of the coupling sleeves and when tightened draw the sleeves rearwards and bring the flanges 39 into clamped relation with the back wall of the outer shell of the boiler. Sealing washers 41 extend around the central portions of the sleeves and form water tight joints between the flanges 39 and 75 the hole forming portions of the back wall 13.

In order to disconnect the hot water coil 10 from the pipes 32 and 33 it is only necessary to remove the pipes from the sleeves 35 of the detachable connections 34 and then remove the nuts 36. Upon removal of the nuts the coil 10, together with the sleeves, is released and may be shifted forwards within the combined water and steam chamber 18 out of connected relation with the pipes 32 and 33. The holes 37 are disposed directly over the smoke box 29 with the result that the pipes 32 and 33 overlie the box. In order to provide for removal of the hot water coil 10 for cleaning or replacement purposes a rectangular opening 42 is formed in the front wall 12 of the outer shell of the boiler directly over the flue door 31. This opening is normally closed by a plate 43. The latter is removably secured in place by means of nut equipped studs 44 which are anchored in or suitably secured to the portion of the front wall 12 which defines the opening 42. A rectangular gasket 43a fits between the margin of the plate and the adjacent opening forming portion of the front wall 12 and forms a fluid tight joint whereby water in the chamber 18 is prevented from leaking from the outer shell via the opening 42 when the plate 43 is in place. The opening 42 is preferably positioned in registry or horizontal alignment with the coil 10 with the result that when the coil is disconnected or detached from the pipes 32 and 33 it may be removed through the opening merely by shifting it forwards in a substantially horizontal plane. In view of the fact that the coil is M-shaped the ends of the coil upon detachment from the pipes 32 and 33 may be readily sprung or urged inwards so as to reduce the width of the coil and thus permit the coil to pass readily through the opening 42. By having the ends of the hot water coil 10 connected to the water inlet and outlet pipes at the back of the boiler the 40 sides and front of the boiler are free from obstruction by pipes and fittings.

The burner 6 is shown in the drawing as being of the oil variety. It is disposed in front of the boiler and comprises a motor driven blower 45 and an air discharge duct 46. The duct leads to and extends through a circular hole 47 in the plate 22 and serves during operation of the burner to discharge air into the combustion chamber. In addition to the blower 45 the 50 burner includes any suitable type of oil pump and atomizer for mixing oil or oil vapor with the air to form a combustible fuel mixture in the combustion chamber. Whereas the burner has been described as being an oil burner it is to be 55 understood that the heating apparatus may be fired by a gas burner or an automatic stoker device.

The jacket 7 surrounds the boiler and burner and constitutes a protective housing or casing therefor. It is fabricated from sheet metal and consists of a pair of side walls 48, a top 49, and a back 50. The sides are arranged in parallel relation and extend forwardly from the back of the boiler a sufficient distance to encase or enclose the burner 6. The top 49 extends between and serves to space the upper margins of the side walls 48 and embodies a central hole 51 for the steam outlet 17. The back 50 extends between the rear side margins of the sides and embodies a single rectangular opening 52 through which the smoke box 29 and the water inlet and outlet pipes 32 and 33 extend. The front of the jacket is closed by means of a pair of doors 53. These doors are hinged to the front side 75

5 margins of the sides and are adapted when in their closed position together with the side walls, top and back of the jacket completely to encase the boiler and burner. The jacket serves not only as a closure for the boiler and burner but also to protect as well as conceal the externally disposed parts of the burner and also the fire and flue doors of the boiler. As shown in Figure 10 of the drawing the doors extend from the top 10 of the jacket to the jacket bottom. Because of this the opening 42 for use in removing the coil 10 is exposed when the doors are in their open position. As a result of the arrangement of the hot water coil 10 and the manner in which it is 15 mounted, it is not necessary to dispose the water inlet and outlet pipes at the sides or front of the jacket where they would not only detract from the appearance as a whole but also obstruct or interfere with ready control and adjustment of 20 the boiler and burner. In addition it is not necessary to cut or form holes in the side walls of the jacket or the doors 53. When these doors are in their open position the plate closed opening 42 is exposed and upon removal of the plate 25 43 from the opening and disconnection of the ends of the coil 10, the coil may be removed as hereinbefore pointed out and without disturbing in any way the various parts of the jacket.

30 The herein described heating apparatus is not only compact but also free from side pipes and may, if desired, be placed with the back wall of the jacket in substantially abutting relation with one of the walls of the furnace room of the home or dwelling in which the apparatus is employed.

Whereas the embodiment of the invention illustrated in the drawing and herein described involves a home heating type of boiler together with an oil burner for firing it and also involves a hot 40 water coil which is associated with a storage tank and is disposed within the chamber 18 so that it is fully immersed in the water in such chamber, it is to be understood that the invention is capable of embodiment in hot water heaters and 45 also boilers of other types which are fired or heated by gas, pulverized fuel, or solid fuel, as well as oil, and in addition that the hot water coil 10 may be of the instantaneous type, that is, of the type which is used without a storage tank 50 and may be either partially submerged in the water in the chamber or arranged so that it is wholly surrounded by steam.

55 It is also to be understood that the invention is not to be restricted to the details set forth, since these may be modified within the scope of the appended claims, without departing from the spirit and scope of the invention.

Having thus described the invention what I claim as new and desire to secure by Letters Patent is:

1. A heating apparatus comprising in combination a boiler embodying side, front, rear and top walls and having a combustion chamber in the bottom thereof and a combined water and steam chamber in its upper portion and also having an opening in the upper part of the front wall communicating with the last mentioned chamber and a removable plate for closing said opening, a domestic hot water coil in the combined water and steam chamber insertable into place through said opening and having the ends thereof leading through a boiler wall other than the front wall and connected to such wall by detachable connections so that upon detachment thereof the 75 coil may be removed through said opening for

cleaning or replacement purposes, a burner in front of the boiler for firing the latter, and a jacket surrounding the boiler and burner and having door means at its front adapted upon opening thereof to expose the plate. 5

2. A heating apparatus comprising in combination a boiler embodying side, front, rear, and top walls and having a combustion chamber in the bottom thereof and a combined water and steam chamber in its upper portion and also having an opening in the upper part of the front wall communicating with the combined water and steam chamber and a removable plate for closing said opening, a domestic hot water coil in said combined water and steam chamber insertable into 10 place through said opening and having the ends thereof leading through the back wall of the boiler and connected thereto by detachable connections so that upon detachment thereof the coil may be removed through said opening for 15 cleaning or replacement purposes, a burner in front of the boiler for firing the latter, and a jacket surrounding the boiler and burner and having door means at its front adapted upon 20 opening thereof to expose the plate. 25

3. A heating apparatus comprising in combination a boiler embodying side, front, rear, and top walls and having a combustion chamber in the bottom thereof and a combined water and steam chamber in its upper portion, and also having an opening in the upper part of the front wall communicating with the combined water and steam chamber and a removable plate for closing said opening, a domestic hot water coil in said combined water and steam chamber in substantial registry with the opening insertable into place 30 through said opening, and having the ends thereof leading through the back wall of the boiler and connected thereto by detachable connections 35 so that upon detachment thereof the coil may be removed through said opening, a burner in the front of the boiler for firing the latter, and a jacket around the boiler and burner embodying sides and a top and back and having door means adapted to close the front thereof and upon opening to expose the plate in the upper part of the 40 front wall of the boiler. 45

4. A heating apparatus comprising in combination a boiler embodying side, front, rear and top walls and having a combustion chamber in the bottom thereof and a combined water and steam chamber in its upper portion, and also having a horizontally elongated opening in the upper part of the front wall communicating with the combined water and steam chamber and a removable plate for closing the opening, a substantially horizontal domestic hot water coil of slightly greater width than the opening disposed in said combined water and steam chamber and having the ends thereof arranged to define its sides and leading to and detachably connected to the back wall of the boiler and adapted upon detachment thereof from the back wall to be sprung inwards so as to reduce the width of the coil and permit the latter to be removed through the opening, a burner in front of the boiler for firing the latter, and a jacket surrounding the boiler and burner and having door means at its front adapted upon opening thereof to expose 60 the plate. 65

5. A heating apparatus comprising in combination a boiler embodying side, front, rear and top walls and having a combustion chamber in the bottom thereof and a combined water and steam chamber in its upper portion, and also 70 75

having a horizontally elongated opening in the upper part of the front wall communicating with the combined water and steam chamber and a removable plate for closing the opening, an M-shaped substantially horizontal domestic hot water coil of slightly greater width than the opening disposed in said combined water and steam chamber in substantial alignment with said opening and having the ends thereof leading 10 through and connected detachably to the back wall of the boiler and adapted upon detachment thereof from the back wall to be sprung inwards so as to reduce the width of the coil and permit the latter to be removed through the opening, a 15 burner in front of the boiler for firing the latter, and a jacket surrounding the boiler and burner and having door means at its front adapted upon opening thereof to expose the plate.

6. In a heating apparatus of the character described, the combination of a boiler embodying side, front, rear and top walls and having a combustion chamber in the bottom portion thereof and a combined water and steam chamber in its upper portion and also having an exteriorly disposed smoke box at the upper portion of the back wall and a plate closed opening in the upper part of the front wall communicating with the combined water and steam chamber, a domestic hot water coil disposed in the last mentioned chamber 30 in substantial alignment with the opening and having the ends thereof leading through the back wall of the boiler at a point above the smoke box and connected to the back wall by detachable connections and adapted by way of said connections 35 for attachment to water inlet and outlet pipes at the back of the boiler and upon detachment to permit the coil to be shifted forwards and removed through said opening, a burner in front of the boiler for firing the latter, and a jacket 40 around the boiler and burner embodying sides and a top and a back wall between the rear margins of the sides and the top and with a single opening therein for accommodating the smoke box and said water inlet and outlet pipes, and 45 provided with door means at its front adapted upon opening thereof to expose the plate closed opening.

7. A boiler comprising in combination an outer shell embodying side, front, rear and top walls and having a horizontally elongated opening in the upper part of the front wall, an inner shell disposed in the central portion of the outer shell and defining with the latter a combustion chamber in the lower portion of the boiler and a combined water and steam chamber in the upper portion of the boiler, a plate for closing said opening secured removably to the front wall of the outer

shell, and a domestic hot water coil in the combined water and steam chamber insertable into place through said opening and having the ends thereof leading through the back wall of the boiler and connected thereto by detachable connections so that upon detachment thereof and removal of the plate the coil can be removed through the opening. 5

8. A heating apparatus comprising in combination a boiler embodying side, front, rear and top walls and having an opening in the upper part of the front wall, and also having a combustion chamber in the lower portion thereof and a water heating chamber above the combustion chamber and in communication with the opening, 10 removable means for closing said opening, and a domestic hot water coil in the water heating chamber insertable into place through said opening and having end parts leading through a boiler wall other than the front wall and connected to 20 such wall by detachable connections so that upon detachment thereof and removal of the closing means the coil can be removed through the opening. 15

9. A heating apparatus comprising in combination a boiler embodying side, front, rear and top walls and having an opening in the upper part of its front wall, and also having a combustion chamber in the lower portion thereof and a water heating chamber above the combustion 25 chamber and in communication with the opening, removable means for closing said opening, and a domestic hot water coil in the water heating chamber insertable into place through the opening and having end parts leading through the 30 back wall and connected thereto by detachable connections so that upon detachment thereof and removal of the closing means the coil may be removed through the opening. 35

10. A heating apparatus comprising in combination a shell embodying side, front, rear and top walls and having a horizontally elongated opening in the upper part of the front wall, and also having a combustion chamber in the lower part thereof and a water heating chamber above 40 the combustion chamber and in communication with the opening, a plate for closing said opening secured removably to said front wall, and a domestic hot water coil in the water heating chamber and insertable into place through said opening 50 and having the ends thereof leading through the back wall of the shell and connected thereto by detachable connections so that upon detachment thereof and removal of the plate the coil can be removed through the opening. 55

WILLIAM ANDERSON.
